J. N. DUNCAN

By
Carl M. Sinclair
Atty.

UNITED STATES PATENT OFFICE.

JOHN N. DUNCAN, OF BOONE, IOWA.

WINDOW LATCH.

1,411,006.

Specification of Letters Patent. Patented Mar. 28, 1922.

Application filed July 16, 1920. Serial No. 396,786.

To all whom it may concern:

Be it known that I, JOHN N. DUNCAN, a citizen of the United States of America, and resident of Boone, Boone County, Iowa, 5 have invented a new and useful Window Latch, of which the following is a specification.

The object of this invention is to provide improved means for supporting a sash of a 10 car-window at a predetermined elevation.

A further object of this invention is to provide an improved construction for a gravity-operated latch.

A further object of this invention is to 15 provide improved means for pivotally mounting a latch.

A further object of this invention is to provide improved means for protecting a jamb from wear by a latch.

20 A further object of this invention is to provide an improved construction for a strike member adapted to be mounted on a sash and be engaged by a latch.

A further object of this invention is to 25 provide a latch adapted to be mounted pivotally, and for gravity operation into latching position, on a window frame and a strike member fitted to and adapted to engage said latch and be supported thereby, 30 said strike member being adapted to be fixed to a sash.

35 My invention consists in the construction, arrangement and combination of elements hereinafter set forth, pointed out in the claims and illustrated by the accompanying drawing, in which—

Figure 1 is an elevation, partly in section, of a window frame and sash, showing my improved devices mounted in latching position but out of engagement. Figure 2 is an elevation, partly in section, at right angles to Figure 1, the parts being shown in the same relative positions. Figure 3 is a top view of the latch device in un-latching position, a portion of the handle being broken away. Figure 4 is a side elevation of the latch plate including the flange omitted in Figure 2.

Figure 5 is an edge view of a portion of 50 a sash, showing a modified form of engaging means for the latch.

In the construction and mounting of the devices as shown the numeral 10 designates a latch plate which is formed with parallel 55 flanges 11, one of which is shown in Figure 2, of less length than the plate and extend-

ing, in spaced relation, from the rear face and adjacent the side margins of the plate. The latch plate 10 is formed with an angular hole 12 in its central portion, which hole is 60 of substantially the same width as the space between the flanges 11. The latch plate 10 also is formed with screw holes near its ends. Registering holes 11', generally circular in form, are formed in the lower end portions 65 of the flanges 11 and one of said holes, in the flange removed in Figure 2, is formed with a key-way 11" opening to its upper portion. A latch 13 is mounted loosely in the space between the flanges 11 and substantially fills the width of said space. The latch is formed with a hole 14, generally circular in form, adapted to register with and of the same size as the holes on the flanges 11, near its lower end and said hole 70 is formed with a key-way 15 opening to its upper portion and adapted to register at times with the key-way in the foremost flange. A latch-handle 16, of elbow shape, has one end-portion formed to extend 80 through the holes in the flanges and latch in register and journal in the holes in the flanges; said portion of the handle being provided with a feather or key 17 adapted to pass through the key-way in the flange 85 and engage in the key-way in the latch. The feather or key 17 tends to hold the handle against lateral movement out of the holes, after it has been mounted manually by hand-register of the key-ways. The 90 latch-handle is formed with a thumb-piece or lug 18 on its outer end. The latch 13 also is formed with a lug 19 on its central portion adapted to project through the angular hole in the latch-plate 10 and also is 95 formed with a lip 20 on its upper end fitted to and adapted to engage the plate 10 at the upper margin of the angular hole 12. The lug 19 is formed with a plane upper face 21 forming an acute angle with its front 100 face 22 and adapted to form, when in latching position, a right angle with the plane of the latch-plate 10. The latch-plate 10 and flanges 11, carrying the latch and handle, are adapted to be mounted in a mortise in a 105 jamb 23, a portion at each end of the mortise being of less depth than its central portion to seat end portions of the plate, and the plate may be secured as shown by screws 24 mounted through the screw-holes therein 110 and seated in the jamb. The mortise in the jamb is formed at and opens to the bot-

tom of a slide-way 25 in which one side portion or stile 26 of a sash is mounted and adapted to slide, the opposing jamb (not shown) being provided with a similar co-
5 acting slide-way of common form to accommodate the opposite stile of the sash. Gains or notches are formed in the lower portion of the outer face, the side face and across the bottom of the stile 26 and a metal
10 strike-member 27 is countersunk therein and secured to the stile. The strike member 27 is angular in cross-section and embraces one edge of the stile 26 within the gains or notches and the lower end portion thereof
15 is formed with a flat lug 28, lying in the notch in the bottom of the stile and forming right angles with the front, rear and side faces of the stile. The lower face of the flat lug 28 is adapted to engage and rest
20 at times on the flat face 21 of the lug 19 on the latch 13, when the latter is in latching position as shown, whereby the sash is supported at predetermined elevation by said latch. A portion 29 of the mortise in
25 the jamb 23 extends laterally from the body of the mortise to accommodate the handle 16 for oscillation therein, and a protecting plate 30 formed with a notch 31 is mounted on the jamb; the notch 31 registering with
30 the portion 29 and loosely embracing the handle. The protecting plate 30 is positioned wholly at one side of the slideway 25. The lower end of the sash preferably is
35 beveled to contact with and fit the upper surface of a window sill 32 and the strike member 27 is beveled to correspond therewith. Any suitable number of screws 33 in either or both flanges of the strike member 27 may be employed to secure it to the
40 stile 26. The latch device and protecting plate may be located at any desired elevation, and a plurality of them may be employed at different elevations to support the sash in any spaced relation to the sill
45 32; and, when the parts are arranged to support a sash, an upward manual movement of the handle 16 is necessary to remove the latch from latching position. Also, on account of the coaction of the flat face 21 with
50 the flat bottom face of the lug 28, it is necessary to raise the sash manually before oscillating the latch 13 to releasing position. These arrangements and elements tend to stable positioning and support of the sash
55 and prevent accidental descent thereof, thus avoiding risk of injuring a hand, arm or other member extended beneath said sash. All of the elements, except the screws, may be made of metal by molding, thus providing for their production economically, owing to the simple lines and construction thereof. Very little machining is required and it is of the simplest character, thus making convenient and economical the assembling of
65 the device.

In Figure 5 I have shown a different form of latch strike or engaging member adapted to be secured to a sash at a point above the lower margin thereof. A plate 34 is countersunk in the outer face of the stile 26 and secured by means of screws 33. The plate 34 is formed with a rectangular hole 35 adapted to receive the lug 19 of the latch member to support the sash in open position. The plate 34 may be placed at any desired point between the upper and lower ends of the stile, and when the latch is in engagement therewith it is entirely hidden from view.

It is to be understood this latching device may be applied to other than car-windows if desired, and I do not desire to be understood as limiting myself to the precise use and arrangement herein shown and described.

If desired the latching device may be inverted and placed at a point high enough to engage above the upper rail of a sash to latch the sash in closed position; or to limit upward movement thereof to any desired degree, thus adapting it to a burglar-proof lock or latch which will permit the sash to be opened sufficiently to provide ventilation and yet prevent the entrance of an unauthorized person through the window opening. The handle 18 might be rearranged so that when in inverted position the tendency of the latch will be to remain open through force of gravity.

I claim as my invention—

1. A car-window latch comprising a latch plate adapted to be mounted in a window jamb and formed with a hole opening through the front of the jamb, a latch mounted for oscillation on said plate and formed with a member adapted to project through said hole in said plate, and a strike member adapted to be mounted on a sash and adapted to engage said projecting member of the latch at times, said latch also being formed with a lip adapted to engage said plate at one margin of said hole to limit oscillatory movement of said latch in one direction when the sash is raised above the level of said latch.

2. A car-window latch comprising a latch plate adapted to be mounted in a window jamb, a latch mounted for oscillation on said plate and formed with a member, having a flat contact face, adapted to project through said plate, and a strike member adapted to be mounted on a sash and formed with a flat contact face adapted to engage the flat contact face on the latch member at times, said latch being provided with an elbow-shaped handle member extending across the plane of said plate and by gravity tending to move said latch to operative position.

3. A car-window latch comprising a latch plate formed with spaced flanges, the latter being formed with registering holes one of which holes is formed with a key-way, the

plate being formed with an angular hole, a latch mounted between said flanges and having a hole with a key-way registering with the holes of the flanges, said latch being 5 adapted to be so turned as to register said key-ways, said latch being formed with a member adapted to project at times through said angular hole, and a handle extending through said holes in the flanges and latch 10 and formed with a feather engaging the key-way in the latch, said projecting member being adapted to be engaged by and support a sliding sash.

4. In a window latch, a latch plate formed 15 with spaced flanges, the latter being formed with registering holes one of which holes is formed with a key-way, a latch mounted between said flanges and having a hole with a key-way registering with the holes of the flanges, said latch being adapted to be so turned as to register said key-ways, and a 20

handle extending through the holes in said flanges and latch and formed with a feather engaging the key-way in the latch.

5. The combination of a latch device 25 adapted to be mounted on a vertical window-jamb and having a handle projecting away from said jamb, said handle being of elbow shape and extending across the plane of said latch device, gravity tending to move said 30 latch to operative position, a protecting plate on said jamb formed with a notch embracing said handle loosely, and a strike member adapted to be mounted on a vertically-slid- 35 able sash and also adapted to engage said latch-device at times, said engagement being suspendible by manual oscillation of said handle.

Signed at Des Moines, in the county of Polk and State of Iowa, this 9th day of 40 July, 1920.

JOHN N. DUNCAN.
